UNITED STATES PATENT OFFICE.

BENJAMIN R. VANCOTT, OF LOS ANGELES, CALIFORNIA.

DESIGN FOR A LIGHTING-FIXTURE PANEL.

Application filed May 17, 1926. Serial No. 17,746. Term of patent 3½ years.

To all whom it may concern:

Be it known that I, BENJAMIN R. VANCOTT, a citizen of the United States, residing at Los Angeles, in the county of Los Angeles and State of California, have invented a new, original, and ornamental Design for a Lighting Fixture Panel, of which the following is a specification, reference being had to the accompanying drawing, forming part thereof.

In the drawing, the figure represents an

elevational or face view of one panel, embodying my design for lighting-fixture panel a portion of the surface finish being shown, it being understood that the balance thereof within the marginal border involves a mere repetition of such part more fully illustrated.

I claim:

The ornamental design for a lighting fixture panel, as shown.

BENJAMIN R. VANCOTT.
